UNITED STATES PATENT OFFICE

150,262

DESIGN FOR A POWER TAKE-OFF ATTACHMENT FOR SEWING MACHINES

Victor J. Sigoda, Great Neck, Long Island, N. Y., assignor to Man-Sew Corporation, New York, N. Y., a corporation of New York

Application January 27, 1947, Serial No. 136,453

Term of patent 14 years

(Cl. D70—2)

To all whom it may concern:

Be it known that I, Victor J. Sigoda, a citizen of the United States, residing at Great Neck, Long Island, in the county of Nassau and State of New York, have invented a new, original, and ornamental Design for Power Take-Off Attachment for Sewing Machines, of which the following is a specification, reference being had to the accompanying drawing, forming a part thereof.

In Figures 1 and 2 I have illustrated the attachment in mounted position for operative connection with a transverse shaft driven from the main shaft of a conventional type of sewing machine partially shown in broken lines.

I claim:

The ornamental design for a power take-off attachment for sewing machines, substantially as shown and described.

VICTOR J. SIGODA.
